UNITED STATES PATENT OFFICE

2,579,970

COIL SPRING RETAINING ROD

August G. Scampone, Utica, N. Y.

Application December 8, 1948, Serial No. 64,174

3 Claims. (Cl. 5—351)

1

The present invention relates to new and useful improvements in spring assemblies for use with inner springs of mattresses, bed springs, cushions and the like, and more particularly to the provision of a coil spring retaining rod of novel tie wire construction for holding the springs firmly in a fixed assembled relation with respect to each other.

An important object of the invention is to provide a tie wire for inner springs of this character embodying means for securely fastening the tie wires to the springs without requiring the use of clips or other types of fastening devices.

A still further object is to provide a device of this character of simple and practical construction, which is strong and durable, efficient and reliable in use, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a fragmentary perspective view of one of the tie wires;

Figure 2 is a fragmentary perspective view showing a pair of springs held in overlapping relation with respect to each other by the tie wire;

Figure 3 is a bottom plan view illustrating a pair of inner springs held in assembled relation by the tie wires;

Figure 4 is a similar view of a modified arrangement for holding the inner springs in a separated position with respect to each other; and

Figure 5 is a sectional view taken on a line 5—5 of Figure 3.

Referring now to the drawing in detail wherein, for the purpose of illustration, I have illustrated a preferred embodiment of the invention, the numeral 5 designates a rigid wire tie rod and having each end bent to provide right angularly disposed portions 6 and 7 to position the end portion 7 parallel to and at one side of the rod 5. The outer end of end portion 7 is formed with a rearwardly extending hook 8.

Inwardly of the end portions 6 and 7, the rod 5 is formed with a vertical U-shaped loop 9 and a horizontal U-shaped loop 10 inwardly of loop 9.

The rest of rod 5 is formed with groups of loops including a pair of horizontal U-shaped loops 11 and a vertical U-shaped loop 12 between said pair of horizontal loops.

At the junction of the angular end portion 6 with the rod 5 is a short vertical connecting bar 13 and a similar relatively short connecting bar 14 is positioned at the junction of one leg of the horizontal loop 10 with the rod 5 to define arms 9a and 9b at each side of the vertical loops raised above the plane of the horizontal loops. Similar relatively short connecting rods are provided at the junction of one leg of the loops 11 with the rod 5.

The tie rods 5 are constructed of a suitable length for connecting a predetermined number of coil springs 15 in assembled relation with each other, the springs 15 being placed in rows, and one of the tie rods 5 being positioned along one edge of the row of springs in a substantially tangential position as shown in Figure 3 of the drawings.

The hook 8 is engaged over the end convolutions 16 of the spring at the end of the row and with the right angled portions 6 and 7 and the horizontal loops 10 positioned horizontally under the convolutions 16 and with the intermediate loop 9 positioned vertically on the inner side of the convolutions 16. The short connecting bars 13 and 14 compensate for the diameter or thickness of the wire from which the spring is formed to enable the convolutions 16 to rest on the horizontal portions 6, 7, and 10 in a tightly gripped position without necessitating bending of the rod 5.

The intermediate groups of loops 11 and 12 similarly support and engage an adjoining spring 15.

When it is desired to assemble adjacent springs in a position with their end convolutions overlapping, as shown in Figure 3, additional tie rods 17 are placed at the overlapping edges of the springs and with the horizontal portions 6 and horizontal loops 10 underlying the convolution of one spring and the with vertical loop 9 positioned between the pair of overlapping convolutions. The springs are thus locked against shifting movement relative to each other.

When it is desired to assemble the springs in spaced apart parallel rows, as shown in Figure 4, a pair of tie rods 18 are positioned parallel to each other at diametrically opposite sides of the springs 19 and another pair of the rods 20 are similarly positioned at the remaining sides of the springs and at right angles to the tie rods 18 to thus lock the springs against shifting movement in any direction.

By forming the groups of loops 11 and 12 at predetermined spaced intervals in the rod, the springs will be assembled at uniformly spaced

distances from each other in a straight line and a spring assembly can be constructed of an exact length and width without the use of an assembly frame or other commonly employed assembling device.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and within the scope of the appended claims.

Having described the invention, what is claimed as new is:

1. A tie member for connecting the convolutions of a row of coil springs comprising a wire rod having right angled horizontal end portions overlying and underlying said convolutions of the

end springs of the row and terminating in hooks engaging over said convolutions, said rod having intermediate portions subtending and engaging one side of said convolutions of the springs of the row, and said rods being provided with horizontal loops bent therefrom intermediate said portions and which subtend and engage the opposite sides of said convolutions.

2. A tie member according to claim 1 wherein said loops flatly engage said convolutions.

3. A tie member according to claim 1 wherein said portions are provided with vertical loops bent therefrom and lying inside and engaging said convolutions.

AUGUST G. SCAMPONE.
